United States Patent Office.

METALLIC SEAL FASTENER.

RALPH S. JENNINGS, OF NEW YORK, N. Y.*

Letters Patent No. 60,193, dated December 4, 1866.

SPECIFICATION.

TO ALL WHOM IT MAY CONCERN:

Be it known that I, RALPH S. JENNINGS, of the city and county of New York, State of New York, have invented a new and useful Implement for Sealing Metallic Seal Envelopes; and I do hereby declare that the following is a full, clear, and exact description thereof, reference being had to the accompanying drawings, making a part of this specification, in which—

Figure 1 is a side view of the sealing device.

Figure 2 is an enlarged view in section of the metallic seal, showing the method of using the implement.

Similar letters of reference indicate corresponding parts in both figures.

This invention relates to an improved device for riveting or securing together the two parts of my metallic seal for sealing envelopes, as will be hereafter described.

To enable others skilled in the art to understand my invention, I will describe its construction and operation.

Before describing the invention I will describe the object for which it is designed. In figure 2, A represents a flanged eyelet, which is constructed with a short tubular portion, terminating at one end in a circular flange, which latter has several spurs projecting from it. This eyelet A is secured, by means of the spurs, to the body of an envelope beneath the flap thereof. That portion of the seal which is lettered B is a circular disk having a central opening through it, surrounding which is a circular depression for receiving the end of the cylindrical portion of the eyelet A when the parts are sealed. This disk B is secured to the flap of the envelope in the same manner as the eyelet flange is secured to the body of the envelope. Both portions, A B, are applied to the envelope in such manner that when the flap thereof is pressed down the cylindrical portion of the eyelet, A, will pass through the perforation which is through the circular plate B. In order to seal the envelope thus provided with the metallic seal, it is first necessary to spread or flare out the end of the eyelet, and then to rivet this end so that it will turn suddenly over and lie snugly within the annular recess or depression in the upper surface of the disk B, as shown in fig. 2.

To accomplish the sealing of the envelopes in this manner, and with facility, I have invented a device, which consists of a stem a, terminating at its ends in enlarged portions b b', which may have the appearance of the handles of keys. These two portions serve as handles by which to grasp and hold the device firmly in the hand, and they also admit of the device being turned in the act of pressing down the seal. On the enlarged open portion b a conical projection c is formed, which is used for spreading the end of the eyelet previously to mashing down or riveting it; and on the enlarged portion b' a convex or hemispherical knob or stud, d, is formed, for the purpose of riveting the eyelet, as shown in fig. 2. It is necessary to flare or spread out the end of the eyelet before riveting it, and for this reason I employ the spreading and riveting portions c d, and apply them to the same stem a, for convenience in using them both. The device herein described may be made of any suitable kind of metal, and ornamented to suit the fancy.

Having thus described my invention, what I claim as new, and desire to secure by Letters Patent, is—

The implement, as a new article of manufacture, for sealing metallic seal envelopes, which is constructed with a spreading portion c, and a closing or riveting portion d, substantially as described.

RALPH S. JENNINGS.
